(57) **CLAIM**

The ornamental design for a liquid dispenser housing, as shown and described.

DESCRIPTION

FIG. 1 is a top, front, and left side perspective view of a liquid dispenser housing showing our new design;

FIG. 2 is a top, front, and left side perspective view of a liquid dispenser housing showing a second embodiment of our new design;

FIG. 3 is a front elevational view thereof;

FIG. 4 is a left side elevational view thereof;

FIG. 5 is a right side elevational view thereof;

FIG. 6 is a bottom plan view thereof;

FIG. 7 is a top, front, and right side perspective view of a liquid dispenser housing showing a third embodiment of our new design;

FIG. 8 is a top, front, and right side perspective view of a liquid dispenser housing showing fourth embodiment of our new design; and,

FIG. 9 is a top, front, and right side perspective view of a liquid dispenser housing showing a fifth embodiment of our new design.

The broken-line disclosure of various elements in the views are for illustrative purposes only and forms no part of the claimed design.
